CLAIM

The ornamental design for a safety bumper for a trailer tailgate, as shown and described.

DESCRIPTION

FIG. 1 is a bottom isometric view of the safety bumper for a trailer tailgate, showing our new design, in a state of use;

FIG. 2 is a top isometric view thereof;

FIG. 3 is a bottom isometric view thereof;

FIG. 4 is a rear view thereof;

FIG. 5 is a left side view thereof; and,

FIG. 6 is a right side view thereof.

The broken lines illustrating a trailer tailgate frame depict environmental structure that forms no part of the claimed design.

1 Claim, 3 Drawing Sheets
